(57) CLAIM

The ornamental design for a scroll 6-bottle wine rack, as shown and described.

DESCRIPTION

FIG. 1 is a front-left perspective view of a scroll 6-bottle wine rack, showing our new design;

FIG. 2 is a front elevational view thereof;

FIG. 3 is a left side elevational view thereof, the right side elevational view being a mirror image thereof;

FIG. 4 is a back elevational view thereof;

FIG. 5 is a top plan view thereof; and,

FIG. 6 is a bottom plan view thereof.
